UNITED STATES PATENT OFFICE.

EDWIN G. MUMMERY, OF DETROIT, MICHIGAN.

DESIGN FOR A WALL FOR HYDROCARBON-BURNERS.

SPECIFICATION forming part of Design No. 32,164, dated January 30, 1900.

Application filed January 2, 1900. Serial No. 172. Term of patent 14 years.

To all whom it may concern:

Be it known that I, EDWIN G. MUMMERY, a citizen of the United States, residing at Detroit, county of Wayne, State of Michigan, have invented and produced a new and original Design for the Wall of a Hydrocarbon-Burner, of which the following is a specification, reference being had to the accompanying drawings, which form a part thereof.

o In the drawings illustrating my design, Figure 1 is a view in perspective of the wall of a hydrocarbon-burner embodying my design. Fig. 2 is a vertical sectional view of the same on the line 2 2, Fig. 1.

As illustrated in the drawings, the leading and material feature of my design consists of a wall of a hydrocarbon-burner formed with a tubular body A, open at its extremities, said wall formed at the upper portion

thereof with an inwardly-projecting flange ²⁰ a, said flange being formed with a series of recesses a' in its inner edge. The body A is also formed with a series of inwardly-projecting vertical ribs B. The body is, furthermore, also formed with a series of annular kerfs or ²⁵ openings C.

Having described my invention, what I claim as new, and desire to secure by Letters Patent, is—

The design for a wall of a hydrocarbon- ³⁰ burner herein shown and described.

In testimony whereof I sign this specification in the presence of two witnesses.

EDWIN G. MUMMERY.
